Primary Examiner — Kendra Leslie Hamilton(74) *Attorney, Agent, or Firm* — Buche & Associates, P.C.; Bryce A. Johnson; John K. Buche(57) **CLAIM**

We claim the ornamental design for a reversible harness, as shown and described.

DESCRIPTION

FIG. 1 is a top, front, left perspective view of a reversible harness, showing our new design in a first configuration; FIG. 2 is a front elevation view thereof; FIG. 3 is a rear elevation view thereof; FIG. 4 is a top plan view thereof; FIG. 5 is a bottom plan view thereof; FIG. 6 is a bottom, front, right perspective view of the reversible harness of FIG. 1, shown in a condition of use; FIG. 7 is a bottom, front, left perspective view thereof; FIG. 8 is a top, front, right perspective view of the reversible harness of FIG. 1, shown inside-out in a second configuration; FIG. 9 is a front elevation view thereof; FIG. 10 is a rear elevation view thereof; FIG. 11 is a top plan view thereof; FIG. 12 is a bottom plan view thereof; FIG. 13 is a bottom, front, right perspective view of the reversible harness of FIG. 8, shown in a condition of use; and, FIG. 14 is a bottom, front, left perspective view thereof. The broken lines showing a dog in FIGS. 6, 7, 13, 14 depict environmental matter and form no part of the claimed design. in all of the drawings, the broken lines on the pet harness depict stitching that forms no part of the claimed design.

1 Claim, 8 Drawing Sheets(56)
